(57) CLAIM

The ornamental design for a chain trim detail for handbags, as shown and described.

DESCRIPTION

FIG. 1 is a front perspective view of a chain trim detail for handbags showing my new design, displayed in the environment of a handbag;

FIG. 2 is a front view of the chain trim detail for handbags shown in FIG. 1;

FIG. 3 is a rear view of the chain trim detail for handbags shown in FIG. 1;

FIG. 4 is a right side view of the chain trim detail for handbags shown in FIG. 1;

FIG. 5 is a left side view of the chain trim detail for handbags shown in FIG. 1;

FIG. 6 is a top view of the chain trim detail for handbags shown in FIG. 1; and,

FIG. 7 is a bottom view of the chain trim detail for handbags shown in FIG. 1.

The lighter lining on the sides of the bags are intended to show contour, and do not reflect any particular material composition or surface texture.

1 Claim, 7 Drawing Sheets
